UNITED STATES PATENT OFFICE.

OVERTON WINSTON, OF MINNEAPOLIS, MINNESOTA.

HEADLIGHT.

1,280,928.

Specification of Letters Patent.

Patented Oct. 8, 1918.

Application filed July 12, 1916. Serial No. 108,834.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My invention relates to headlights and has for its object to provide an improved socket therefor especially adapted for use with two 15 filament electric light bulbs wherein the filaments are extended diametrically or transversely of the axis of the bulb.

In the accompanying drawings which illustrate the invention, like characters indicate 20 like parts throughout the several views.

Referring to the drawings:

Figure 1 is a vertical section taken centrally through a headlight involved in my 25 invention, some parts being shown in full:

Fig. 2 is a rear end elevation of the lamp socket; and

Fig. 3 is a section on the line 3—3 of Fig. 1.

The numeral 4 indicates a concave reflector provided with a rigid and permanently se- 30 cured rearwardly extended axial tube 5 that constitutes the outer element of the lamp socket. The lamp socket further comprises an inner tube 6 that is telescoped within the tube 5 and is rigidly secured thereto, so that 35 it is held against both endwise and rotary adjustments. Preferably, the said inner tube is thus rigidly held by anchoring lips 7 and 8 integral, respectively, with the tubes 5 and 6, the lip 7 being turned against the outer 40 end of the tube 6 and the lip 8 being bent upward through a notch 9 in the said tube 5 and overlapped with the top at the rear portion thereof. The rear portion of the inner tube 6 is shown as provided with a fixed 45 bushing 10 in which is rigidly secured an insulating plug 11 from which a forwardly spring-pressed contact plunger 12 projects axially.

The socket further comprises a holding 50 collar 13 which has a smooth or simple electric inner end portion 14 rotatably mounted in the front end portion of the socket tube 6. As shown, said eccentric 14, at its inner end, carries a centering ring 15 of insulating material.

The numeral 16 indicates an electric light

bulb having two filaments *a* and *b* connected to three stiff leading in wires 17 supported from the core of the bulb. On the shank of the bulb is a metallic contact sleeve 18 having outstanding lock lugs adapted to be inserted through grooves 20 in the holding collar 13 and to be turned into engagement with a shoulder 21 in the interior of said collar. One of the wires 17 is electrically connected to the collar 18, another is electrically connected to an axial contact 22 on the inner end of the bulb shank, and the other is connected to a contact ring 23 in the rear end of the bulb shank, as shown, for example, in my 70 pending application S. N. 102,440, filed of date, June 8th, 1916, and entitled "Lamp socket". The contact plunger 12 engages the axial contact 22 and the sleeve 18 is grounded through the socket. The numeral 75 24 indicates a coiled spring that re-acts against the insulating plug 11 and against the shoulder of the insulated spacing ring 15, and engages the annular contact 23 of the bulb shank. It will, of course, be understood 80 that of the three wires of the supply circuit, one will be connected to the plunger 12, another to the spring 24, and the other, or third, to the socket.

The socket construction illustrated is especially adapted for use in connection with electric lamps or light bulbs that are made in accordance with the process disclosed and claimed in my pending application S. N. 108,318 filed of date, July 10, 1916 and entitled "Electric light bulb and process of making the same", and which bulbs do not require adjustment axially of the reflector. The present improved socket is not adjusted axially, that is, all of its parts are permanently fixed against axial adjustments, but by rotation of the eccentric socket sleeve and by rotation of the bulb shank within said sleeve, the bulb may be adjusted transversely of the axis of the reflector to compensate for 95 warping of the filaments, and the filaments may be always maintained and positioned in the same vertical plane.

The filament *a* preferably has its hot spot at the axis of the reflector and of the light 105 bulb, while the filament *b* has its hot spot located considerably above the said coincident axes.

What I claim is:

The combination with a reflector having a 110 fixed rearwardly projecting axial outer tube, of a lamp socket made up of an inner tube

22
telescoped within and rigidly directly interlocked to said outer tube and provided with a holding collar having an eccentric portion mounted in said inner tube for rotary movement but held against axial movements in respect to both of said tubes.

In testimony whereof I affix my signature in presence of two witnesses.

OVERTON WINSTON.
